TO LYON & HEALY, OF CHICAGO, ILLINOIS, A CORPORATION OF ILLINOIS.

PEDAL DEVICE FOR PIANOS AND OTHER PURPOSES.

1,412,870.

Specification of Letters Patent. Patented Apr. 18, 1922.

Application filed May 15, 1919. Serial No. 297,381.

To all whom it may concern:

Be it known that we, BENJAMIN H. JEFFERSON and WALTER I. KIRK, citizens of the United States, residing at Chicago, in the 5 county of Cook and State of Illinois, have invented a certain new and useful Improvement in Pedal Devices for Pianos and other Purposes, of which the following is a full, clear, concise, and exact description, reference being had to the accompanying drawings, forming a part of this specification.

Our invention relates to pedal devices, such as are used for pianos and for other purposes.

One of the objects of the invention is to 15 provide a pedal device of the class mentioned which can be acted upon at a point or position above the one which is usually or normally acted or pressed upon.

Another object of the invention is to 20 permit the pedal device to be operated by acting upon it at such usual or normal position, as well as at such elevated point or position.

Another object of the invention is to 25 cure these pressing surfaces at different horizontal levels by means of a construction similar in general shape and character to the usual piano pedal.

Another object of the invention is to 30 range for the easy, ready and quick adjustment of such relatively adjustable parts.

Another object of the invention is to secure simplicity and practicability of construction and operation.

Another object of the invention is to 35 accomplish the foregoing and other desirable results in a simple and expeditious manner.

In the accompanying drawings Fig. 1 is 40 a front elevation of the lower part of the front of a piano provided with three pedal devices embodying our present invention;

Fig. 2 is a vertical section taken on line 2—2 in Fig. 1;

Fig. 3 is a cross section taken on line 3—3 45 in Fig. 2.

Referring to the drawings we show the lower portion 1, of the front of the piano provided with three pedal devices, 2, 3, and 4. The pedal devices 2 and 3 are in position to be played by being acted upon in the usual manner by a full grown person. The pedal device 4 is in condition to be played by a short legged person, such as a child.

Each of the pedal devices 2, 3 and 4 con-

sists of a shank 5 (Fig. 2) which is secured to a pedal bar 6 which is understood to be connected to some suitable mechanism inside of the piano which is to be actuated by actuation of the pedal. The pedal device is also provided with a pedal member 7, preferably of the shape usual to piano pedals and having an upwardly extending portion 8 which extends alongside of the shank 5, and a horizontal portion 9 extending forwardly from the portion 8.

The member 7 is made bodily adjustable with reference to the shank 5 and is mounted so that it may be in substantially reversed position, as shown in dotted lines in Fig. 2 in which the member 9 will be elevated and the entire member 7 upside down. As one effective method of so mounting the member 7, we show a pivot 10 passing through shank 5 and portion 8, whereby the member 7 may simply be rotated about said pivot.

This provides an elevated pressing surface when the member 7 is in the elevated and upside down position, such pressing surface being the surface 9^a which is normally the bottom of the horizontal portion 9 when said member 7 is in its normal position, as shown by full lines in Fig. 2. When the member 7 is in the lower position the usual pressing surface is provided and when in the elevated and upside down position an elevated pressing surface will be provided.

As a matter of further improvement the member 7 is preferably locked in adjusted positions,—that is, in both the lower and elevated positions. As an advantageous arrangement a recess 11 is formed in the member 7 and a pivoted trigger 12 is arranged within this space 11 and supported on the pivot 13. Furthermore, the shank 5 is provided with a recess 14 and trigger 12 has an enlarged end 15 which can fit into said recess or groove 14. There is also a recess 16 for the lower end of the trigger, which end however, projects slightly below the bottom of the member 9 so as to allow easy access and operation of the finger or thumb. A spring 17 is arranged in the upper part of the recess 11 behind the upper end of the trigger 12 tending to push said upper end normally into the recess or groove 14. When the end 15 of the trigger 7 is in such groove or recess, the member 7

will be locked in the position to which it is adjusted. To unlock the member 7 the lower end of the trigger is pushed inwardly, that is, toward the pedal bar 6 and this withdraws the enlargement 15 from the recess or groove 14. Then the member 7 may be swung or rotated about the pivot 10 as desired. In Fig. 2 the trigger 12 is shown locking the member 7 in the lower position. 10 When the member 7 is reversed the enlarged end 15 of the trigger will fit into another portion of the groove 14 and thereby lock said member 7 in the elevated and upside down position. 15 It will be understood that changes and modifications may be made without departing from the spirit of the invention.

What we claim is:

1. A pedal device having a pedal member and means for pivotally mounting the same to permit swinging movement about an axis extending in a direction lengthwise of said member. 20
2. A pedal device having a pedal member and means for pivotally supporting the rear portion of said pedal member to permit the same to be turned upside down. 25
3. A pedal device having a pedal member and means for pivotally supporting the rear portion of said pedal member to permit the same to be turned upside down, and means for locking said pedal member in upside down position. 30
4. A pedal device having a pedal member, means for pivotally supporting the rear portion of said pedal member to permit the same to be turned upside down, and 35

means for locking said pedal member in upside down position, and also for locking 40 the same in lowered position.

5. A pedal device having a pedal member, means for pivotally supporting the rear portion of said pedal member to permit the same to be turned upside down, and means 45 for locking said pedal member in upside down position, said means comprising a trigger and groove arrangement, the parts of which are on the pedal and the part to which the pedal is connected. 50

6. A pedal device having a pedal member and means for pivotally supporting the rear portion of said pedal member to permit the same to be turned upside down, and means for locking said pedal member in upside 55 down position, said means comprising a pivoted trigger carried by the pedal member and a groove formed in the support to which the pedal is pivoted and a spring tending to engage said trigger with said 60 support.

7. A pedal device comprising a shank mounted on a pedal bar and a pedal member connected by a horizontal pivot with said shank, said pedal member being provided with a spring controlled trigger, one end of which is adapted to engage and lock in a groove in said shank, and the other end of which projects below the bottom surface of said pedal member. 70

In witness whereof, we hereunto subscribe our names this 24th day of April, A. D., 1919.

BENJAMIN H. JEFFERSON.
WALTER I. KIRK.
